[57] CLAIM

The ornamental design for a combined door stop and latching device, as shown and described.

DESCRIPTION

FIG. 1 is a perspective view of a combined door stop and latching device, showing my new design;

FIG. 2 is a side elevational view of the side not seen in FIG. 1;

FIG. 3 is a top plan view thereof;

FIG. 4 is a front elevational view thereof; and

FIG. 5 is a rear elevational view thereof.

The rear is unornamented.
